UNITED STATES PATENT OFFICE.

GEORGE WARGA, OF HOBOKEN, NEW JERSEY.

PUZZLE.

1,269,233.

Specification of Letters Patent. Patented June 11, 1918.

Application filed November 15, 1916. Serial No. 131,447.

To all whom it may concern:

Be it known that I, GEORGE WARGA, a subject of the Emperor of Hungary, resident of Hoboken, county of Hudson, and State of New Jersey, have invented certain new and useful Improvements in Puzzles, of which the following is a specification.

This invention relates to improvements in toys or puzzles and has as its principal object the provision of certain peculiarly formed flat plates or blocks which may be arranged upon a flat level surface in a wide variety of forms.

A further object is to combine with the edges of said blocks joint strips whereby the blocks may be held in intimate connection one with another, so that when arranged in any special design that the several blocks are held in position.

These and other objects are attained by the novel design, construction and combination of parts hereafter described and shown in the accompanying drawings, forming a material part of this specification, and in which:

Figure 1 is a plan view showing one of the many forms in which the blocks may be placed.

Fig. 2 is a similar view showing another assemblage of the blocks.

Fig. 3 is an enlarged plan view of one form of the blocks employed.

Fig. 4 is an enlarged transverse sectional view taken on line 4-4 of Fig. 3.

Fig. 5 is a plan view showing the other form of block.

Fig. 6 is an enlarged transverse sectional view taken on line 6-6 of Fig. 5.

Fig. 7 is a fragmental plan view, partially in section, showing adjacent blocks as connected.

Fig. 8 is a transverse sectional view taken on line 8-8 of Fig. 7, and

Fig. 9 is a perspective view showing one of the engaging elements used between adjacent blocks.

The invention comprises the use of two relatively thin plates or blocks of wood, paper or other material, such as are indicated in Figs. 3 and 4, and from which it will be seen that one of the blocks 10 presents in outline, the frustum of a flattened

cone having a base 11 and upper surface 12 joined by oblique sides 14, the upper and lower surface of the block, which is of uniform thickness, presenting smooth and level sides.

In the four edges of the block are formed lineal grooves 15 extending completely from end to end and central with the thickness of the block. The other block 20 is in effect a triangle having a base 21, and sides 22, terminating in a sharp apex 23, similar lineal grooves 25 being formed in the sides and base, the length of the base being equal to that of the end 12 of the larger block.

The recesses 15 and 25 are suited to receive a connecting strip 26, the same fitting neatly in the grooves so that when two adjacent blocks are placed closely side by side with the strip 26 within the grooves that no opening appears between the blocks, as will be clearly evident from an inspection of Figs. 1 and 2.

From the foregoing it will be seen that by the use of blocks formed in the manner indicated, a wide variety of articles may be formed, the profiles of which may represent animals or things in a peculiar novel manner, and as there are but two different forms of blocks employed together with a single form of engaging element that the device is of an extremely simple character.

It will be obvious that when the blocks are in any design, that the outline may be traced upon a sheet of paper or slate so as to afford instruction and amusement in recording design thus shown.

Having thus described my invention, what I claim as new and desire to secure by Letters Patent, is:

In combination two blocks, one of said blocks being in the form of a trapezoid having oppositely-inclined sides and a long and short side arranged in parallelism, the other block being in the shape of a triangle having its base of even length with that side of the trapezoidal block which is shortest so that when the homologous sides of both blocks contact the inclined sides of both blocks form the opposite sides of a triangle.

In testimony whereof I have affixed my signature this 9th day of November, 1916.

GEORGE WARGA.
